UNITED STATES PATENT OFFICE.

GEZA STEPHAN FISCHER, OF BERLIN, GERMANY.

AUTOMATIC CIRCUIT BREAKER.

Application filed June 23, 1925, Serial No. 39,139, and in Germany April 18, 1925.

This invention relates to an improved automatic circuit breaker particularly intended or designed and adapted for use in connection with an electric flat-iron.

Stands for electric flat-irons have been suggested heretofore in which means are provided for automatically breaking the circuit through the weight of the iron as soon as the latter is placed upon the stand. Stands of this type are commonly equipped with quick-break switches of the kind generally employed in connection with lighting circuits, but switches of this kind frequently fail to work to satisfaction in connection with smoothing-irons requiring considerably higher loads than a mere lighting circuit. For in switches of the stated kind a voltaic arc will sometimes be produced even in case of a slight unevenness of the contacting surfaces only and the arc thus struck at a load of say 220 volt and 450 watt may have a length of 12 to 14 mm. and will not disappear, unless the length of the gap increases owing to the contact surfaces melting off to a certain amount.

The object of this invention is to remedy this defect and with this object in view I provide a plurality of pairs of contact surfaces, by way of division in order to avoid sparking, so that each circuit breaker will have at least two pairs of contacts reciprocally acting as blow-out contacts upon each other.

The contact-lever, in this case, will act to multiply the minute breaking movement occurring subsequently to placing the flat-iron upon the stand.

With the above recited and other objects in view reference is had to the following specification and drawings in which there is exhibited one example or embodiment of the invention which is in no way intended as a limitation upon the scope of the appended claims as is to be clearly understood that variations and modifications which properly fall within the scope of said claim may be resorted to when found expedient.

In the drawings Figure 1 is a sectional elevation showing the new device in position of rest; Figure 2 is a similar view illustrating the device in working position prior to the breaking of the contact; Figure 3 is a similar view showing the device in working position after the breaking of the contact, and Figure 4 is a plan view of the contact lever, as well as a partial plan view of

the brackets on the top of the casing *i* for coacting with the contact levers.

Parts which are repeated in the several figures bear the same reference characters in each case.

Referring to the drawings the circuit breaker comprises a casing *a*, a push-bolt *b*, springs *c* and *d* coiled about the bolt *b*, limiting pins *e* and *f* in the bolt *b* for the two springs to abut against, a contact lever *g* and a contact *h* yieldingly fixed to a base-plate *i* supporting the several parts when assembled as shown in the drawings.

The top of the casing *a* and the base-plate *i* have each an opening and the two openings are vertically alined to act as a guiding means for the push-bolt *b* housed within the casing *a* with freedom to move vertically or lengthwise therein. The reciprocatory movement of the bolt is controlled by the two springs. The side walls of the casing *a* have two slots diametrically opposite each other for the lever *g* to pass therethrough and the lever *g* has an elongated slot *k* for the bolt *b* to pass therethrough, the said slots being sized to allow the lever to freely play as required for a proper operation. The spring *c* is located between the upper pin *e* and the lever *g* so as to engage the latter in the vicinity of the slot *k* whilst the spring *d* is inserted between or to abut against the lower pin *f* and the base-plate *i* so as to contact with the latter in close proximity to the opening thereof. The opposite end of the lever *g* is bifurcated as at 1 and the bifurcated portions are formed with contact ears *m* which are adapted to contact with the sides of the contact brackets *n* on the base when the free end of the lever *g* is in engagement with the upper part of the contact *h* so that in the event of a faulty connection at *h* the circuit will be made and broken by the coaction between elements *m* and *n*.

While in condition of rest the parts of the breaking device have adopted the positions shown in Figure 1. Now, if the push-bolt *b* is forced down under a load or weight, the pin *e* will act to compress the spring *c* on the lever *g* and, at the same time, the pin *f* will act to compress the spring *d* on and against the base-plate *i*, so that a clear way produced in the casing below the lever *g* for the latter to descend, as will be readily understood on an inspection of Figure 2.

Upon the continued movement of the bolt

2
b under the load of weight the spring *c* will be compressed more and more until the same is sufficiently stressed to overcome the friction between the lever *g* and the yielding contact *h* whereupon the lever *g* is rapidly forced down within the clearance between the two springs, that is to say, from the position shown in Figure 2 to that illustrated in Figure 3, and as soon as the load to 10 turn the parts again to the original position shown in Figure 1.

What I claim is:—

An automatic circuit controller of the character described comprising a base plate, 15 spaced contacts thereon, a casing mounted on the base plate and positioned between the

contacts and provided with opposed openings in the side walls, a contact lever pivoted to the casing for vertical swinging movement and arranged through the openings therein 20 for cooperating with the contact, a bolt vertically slideable through the casing lever and base plate, and coiled springs arranged above and below the lever and about the bolt and having their upper ends connected to the 25 bolt, the upper spring acting to accelerate the short movement imparted to the pin and the lower spring acting to automatically return the parts to normal position, substantially as and for the purposes set forth. 30

In testimony whereof I affix my signature.

D. Ing. GEZA STEPHAN FISCHER.
